UNITED STATES PATENT OFFICE

ENOS H. KREIDER, OF LANCASTER, PENNSYLVANIA

VEHICLE SHOCK ABSORBER

Application filed August 6, 1929. Serial No. 383,798.

The object of this invention is to provide a device which will automatically eliminate practically all undesirable disturbances to the body of the vehicle while it is passing over inequalities of the roadbed and which at the same time will automatically (i. e., without manual intervention) adjust itself to different vehicle loads, to the end that, whatever the load may be and no matter how often it may be changed, the shock-absorbing capacities of the device as well as its relieved center action will remain the same, as more fully hereinafter set forth.

In the drawings—

Fig. 1 is a horizontal sectional view, looking upwardly, and

Fig. 2 is a vertical transverse sectional view of a device embodying a desirable form of my invention;

Fig. 3 is a detail top view of the valve-controlling devices;

Fig. 4 is a detail plan of the cover-plate of the pressure-chambers;

Figs. 5 and 6 are diagrams showing the parts in different positions;

Fig. 7 is a detail view of the strainer.

Referring to the drawings annexed by reference characters, 10 represents the cylindrical casing which is provided with the usual lugs 11 for fastening the same to the chassis and in which is journaled the usual horizontal rock-shaft 12 which is connected by an arm 13 in the usual manner to one of the axles, this latter connecting means not being shown because it is common in this art. Screwed to the exterior of the cylindrical casing 10 is an oil-reservoir shell 14 having a filling-plug 15, an oil-tight joint for this screw connection being provided by means of a screw-ring 16 and a packing 17. The shaft 12 is journaled in a tubular bearing 18 between whose outer end and the shell 14 a packing-ring 19 is arranged to make an oil-tight joint between shell 14 and the shaft 12. This cylindrical bearing 18 is fastened in the outer end of the cylindrical casing 10 by means of a disk 20 which is screwed into said casing against a cover-plate 21 fitted into the

casing 10 against an outwardly-facing internal shoulder.

The cover-plate fits down against the upper side of a head-bar 22 fitted into the cylindrical casing and extending horizontally thereacross. Within the chamber, underneath the head-bar 22, vibrates the vane-piston 23 which is affixed to the inner end of the rock-shaft 12, the outer edge of this vane-piston working against the interior of the cylinder 10 in the usual manner and being adapted to oscillate, in the usual manner, with the shaft 12. The usual choke-passages 24 connect the oil-chambers at opposite sides of the piston to the interior of the shaft 12, where a valve-seat 25 is formed, so that the choke-passages may be controlled by means of a valve 26 arranged axially in the shaft 12. Certain additional oil-passages 27 and 28 are provided for lubricating purposes.

An oil relief-passage 29 extends from each pressure-chamber, through the bar 22, out through the outer face of the bar, so that they shall be always in communication with each other through the oil-reservoir 14. The cover-plate 21 is cut out so as to avoid covering these oil-passages 29, outwardly-projecting pins 30 being provided on the bar 22 for positioning the cover-plate so as to always prevent it interfering with the free passage of oil through these passages 29. Over each of the relief-passages 29 is arranged a reed-valve 31 which is adapted to spring to full-open position toward its associated pressure-chamber, whose affixed rock-shaft 32 extends up through the bar 22 and projects slightly beyond the upper face of said bar. Each of the valves 31 is held normally partially open by an arm 35 affixed to the aforesaid projecting end of said rock-shaft 32, these two arms being held in their normal position (i. e., in position to hold the valve 31 laterally partially open) by means of a retractile spring 36 which connects the arms 35 and holds said arms 35 normally against stop-pins 37. Arranged to vibrate in the path of the outwardly-extending ends of arms 35 is a pair of fingers 38 carried by a spring-clamp 39 frictionally embracing the rock-shaft 12. In order to maintain these

fingers 38 in or near central position (i. e., in a position where the levers 35 hold both valves partially open, as shown in Fig. 2), I provide a central pin 40 which projects rigidly from the outer face of the bar 22.

The disk 20 is provided with a plurality of holes 41 for the passage of oil from and to the relief-passages 29, and over all these holes is arranged a gauze strainer 42; the object of this arrangement is to prevent objectionable 10 impurities entering the pressure chambers and thus interfering with the proper operation of the piston and valves.

With a normal load on the vehicle, the 15 parts will be in the position shown in Fig. 2, in which position both valves 31 will be held partially open and the piston therefore will have a greater freedom of action in either direction during minor vibrations, that is, so long as the vehicle is running on a relatively-smooth road and there is therefore no need for bringing the shock-absorber into action. The instant, however, the wheel or wheels of the vehicle drop into a depression or are 20 thrown up by an obstacle sufficient to impart a major vibration, one or the other of the fingers 38 will swing its associated lever 35 laterally far enough to swing its associated valve 31 to full closed position, while the companion valve 31 will remain open. In such case, the direction of movement of the piston will be toward the open valve, so that the initial movement, whether it be up or down, will not be materially hindered and the vehicle 25 springs therefore will have just enough of resistance to stabilize their action. Upon return, however, of the piston, under the recoil of the vehicle-springs, the piston will move toward the closed valve and thus instantaneously set up an increased resistance against the movement of the piston, forcing the oil through the choke-passage 24. Assuming another major vibration or jounce in the opposite direction, the same action will take place 30 in a reverse order. In this operation of the device, the spring-band 39 will not have any movement relative to the shaft on which it is clamped, as only in possible rare instances will the movement be great enough for either 35 one of the fingers 38 to strike against the central readjusting pin 40. It will be observed further that the restraint is continuous throughout the entire correcting movement of the device, and that, if excessive road conditions are encountered on both sides of the relieved center area, the restraint of the device is continuous both ways, restraining right through the relieved center area but immediately partially opening both valves when 40 the vehicle again begins to run on a relatively-smooth roadbed. It will be seen further that during the period of time in which the valve 31 is closed and the vane 23 is moving toward the same valve, the lever 35 associated therewith will be free (so far as fin-

gers 38 are concerned) to return to its original position with its valve 31 again in partially open position, but it will be understood that so long as the piston is approaching said valve the pressure of the oil against the valve will be sufficient to prevent the spring 36 acting to return the valve to its home position until the instant the movement of the piston toward the valve ceases, at which instant spring 36 will act to return the valve to its home, or partially open position. 70

It will be observed that each valve 31 consists of a plate of spring metal so that, even when it is in an entirely-closed position, as shown in dot-and-dash lines at the extreme right-hand end of Fig. 3, the valve is free to open inwardly by reason of the suction action exerted by the piston in its movement away from said valve, so that in all cases the oil will have free access to each pressure-chamber whenever the piston is moving away from its valve 31. It is desirable to so arrange each reed-valve 31 that in its home position (shown in dotted lines at the left-hand end of Fig. 3) it shall only partly cover its port 29 so that even an initial major movement of the piston toward the valve will be more or less restricted, whereas in every movement of the piston away from the valve said valve offers 95 practically no resistance to the entrance of oil through port 29. 90

In the foregoing description of the operation of the device, I have assumed that the vehicle is carrying a normal load and that the piston 23 is virtually at center, i. e., midway between the two valves. Should the load of the vehicle be increased or decreased, however, the piston will be shifted to one side or the other to a degree corresponding with the change in load, and the spring-band 39 together with its fingers 38 will be carried with the rotation of the shaft 12 until they meet stop-pin 40, at which time the shaft will turn within the spring-band. The piston will remain in approximately this shifted position (which represents a new central position of the movements) so long as the load remains the same, and the spring-band with its fingers will also remain in the shifted position until the vehicle has been driven some distance, this distance depending generally upon the character of the roadbed. In any case, however, the slight jouncing of the axle will be sufficient to quickly restore the band and the fingers to central position with respect to the pin 40 and the valve-operating levers. This shifting of the band back to central position will be caused principally by one of the fingers 38, namely, the one nearest the pin 40, repeatedly striking against said pin 40 until the band has been slid backwardly far enough on the shaft 12 to centralize the fingers with respect to said pin 40 (as shown in dotted lines in Fig. 6), 125

5 after which the relieved center functioning will be resumed without regard to whether the piston 23 is nearer to one of the valves 31 or the other. In this way, my device automatically (i. e., without the intervention of any manual manipulations of any of the parts) readjusts itself after each change of vehicle load, to the end that, whatever the load be, the shock-absorber functions in the 10 same way as with what might be called a normal load, i. e., a load which would centralize the piston 23.

15 In the diagram, Fig. 5, I show the initial position of the parts upon a load decrease, and in Fig. 6 I show the initial position of the parts upon increasing the load above normal.

What I claim as new is:

20 1. In a vehicle shock-absorber of the hydraulic type embodying a rock-shaft carrying a vane-piston and means forming a pressure-chamber at each side thereof, an inwardly-opening valve for each of these pressure chambers, devices for normally holding these valves open to thereby permit a free-center movement of the vane-piston, and devices whereby a major vibration of the unsprung portion of the vehicle will rock the 25 said shaft sufficiently to positively close one of said valves while holding the other open.

30 2. In a vehicle shock-absorber of the hydraulic type embodying a rock-shaft carrying a vane-piston and means forming a pressure-chamber at each side thereof, an inwardly-opening valve for each of these pressure-chambers, devices for normally holding these valves open to thereby permit a free-center movement of the vane-piston, and means whereby a major vibration of the unsprung portion of the vehicle will rock the 35 said shaft sufficiently to close one of said valves while holding the other open, said valves each being of the reed type so as to open with suction even when closed.

40 3. In a vehicle shock-absorber of the hydraulic type embodying a rock-shaft carrying a vane-piston and means forming a pressure-chamber at each side thereof, an inwardly-opening valve for each of these pressure-chambers, devices for normally holding these valves open to thereby permit a free-center movement of the vane-piston, and means whereby a major vibration of the unsprung portion of the vehicle will rock the 45 said shaft sufficiently to positively close one of said valves while holding the other open, said means embodying a band frictionally embracing said rock-shaft and carrying operating-fingers, and a device for automatically shifting said band after a change of load on the vehicle-springs to return said fingers to free-center position.

50 4. In a vehicle shock-absorber of the hydraulic type embodying a rock-shaft carrying a vane-piston and means forming a pressure-chamber at each side thereof, an inwardly-opening valve for each of these pressure-chambers, devices for normally holding these valves open to thereby permit a free-center movement of the vane-piston, and means whereby a major vibration of the unsprung portion of the vehicle will rock the 55 said shaft sufficiently to positively close one of said valves while holding the other open, said means embodying a band frictionally embracing said rock-shaft and carrying operating-fingers, and a device for automatically shifting said band after a change of load on the vehicle-springs to return said fingers to

free-center position, said device consisting of a stop located between said fingers.

5 4. In a vehicle shock-absorber of the hydraulic type embodying a casing, a rock-shaft journaled therein carrying a wing-piston, means in the casing forming a pressure-chamber at each side of the piston, choke-passages being provided for said pressure-chambers and also a relief-passage for each of said pressure-chambers, a valve for each of said pressure-chambers opening inwardly with respect to its associated pressure-chamber, means for normally holding these valves open during minor rocking operations of said shaft and for alternately positively closing said valves upon major vibrations of said shaft, the construction being such that said means will be shifted out of normal free-center position upon change of load on the vehicle-springs, and a device whereby after the parts are shifted to abnormal position by change of load the subsequent vibrations of said shaft will restore the parts to normal free-center position.

10 5. In a vehicle shock-absorber of the hydraulic type embodying a rock-shaft carrying a vane-piston and means forming a pressure chamber at each side thereof, an inwardly-opening valve for each of these pressure chambers, devices for normally holding these valves open to thereby permit a free-center movement of the vane-piston, and devices whereby a major vibration of the unsprung portion of the vehicle will rock the 15 said shaft sufficiently to close one of said valves while holding the other open, said valves each being of the reed type so as to open with suction even when closed.

20 6. In a vehicle shock-absorber of the hydraulic type embodying a casing, a rock-shaft carrying a vane-piston, means for forming within the casing a pressure-chamber at each side of said vane-piston, choke-ports as well as relief-ports being provided for each pressure-chamber, a reed-valve for each relief-port, a rock-shaft carrying each reed-valve, an arm affixed to each rock-shaft, a spring connecting the arms of the rock-shafts to normally hold the reed-valves open, and means whereby a major vibration of the unsprung portion of the vehicle will rock one of said valve-carrying rock-shafts sufficiently to close its valve while leaving the other valve open.

25 In testimony whereof I hereunto affix my 120 signature.
